(57) **CLAIM**

The ornamental design for a nesting seatbelt tongue, as
shown and described.

DESCRIPTION

FIG. 1 shows a perspective view of my design for a nesting
seatbelt tongue;

FIG. 2 is an exploded perspective view thereof;

FIG. 3 is a top view of a first component, bottom view being

a mirror image thereof;

FIG. 4 is a left side view of a first component, the right side

view being a mirror image thereof;

FIG. 5 is a front view of a first component, image thereof;

FIG. 6 is a back view of a first component, image thereof;

FIG. 7 is a top view of a second component, bottom view

being a mirror image thereof;

FIG. 8 is a left side view of a second component, the right

side view being a mirror image thereof;

FIG. 9 is a front view of a second component, image thereof;

FIG. 10 is a back view of a second component, image

thereof;

FIG. 11 is an exploded top view of a first and second

component image thereof;

FIG. 12 is a top view of a first and second component image

thereof;

FIG. 13 is a left side view of a first and second component,

right side view being a mirror image thereof;

FIG. 14 is a bottom view of a first and second component

image thereof;

FIG. 15 is a front view of a first and second component

image thereof; and,

FIG. 16 is a back view of a first and second component

image thereof.

The broken lines shown of the webbing is for illustrative

purposes only and form no part of the claimed design.

The nesting seatbelt tongue of the present invention is
designed to attach to a any length of webbing and be inserted
into a female seatbelt slot.
